Primary Examiner — Catherine Tuttle(74) *Attorney, Agent, or Firm* — Charles J. Prescott**(57) CLAIM**

The ornamental design for a yo-yo, as shown and described.

DESCRIPTION

FIG. 1 is a perspective view of a yo-yo showing my new design;

FIG. 2 is a side elevation view of FIG. 1; and,

FIG. 3 is a top plan view of FIG. 1, the bottom plan view being identical.

The broken line is included for the purpose of illustrating the boundary of a portion of the yo-yo that together with the broken line itself forms no part of the claimed design.
